CLAIM

The ornamental design for an eyeglass lens, as shown and described.

DESCRIPTION

FIG. 1 is a top front perspective view of an eyeglass lens showing the claimed design;

FIG. 2 is a front view thereof;

FIG. 3 is a rear view thereof;

FIG. 4 is a right side view thereof, the left side view being a mirror image thereof;

FIG. 5 is a top view thereof; and,

FIG. 6 is a bottom view thereof.
